COMPOSITE INSULATING MATERIAL

Application filed August 14, 1928. Serial No. 299,581.

Our present invention relates to the manufacture of heat and sound insulating material and padding such as is used in building construction as a lining for walls and floors, and has for its object to provide an improved article of this character. The improvements are directed in part toward furnishing a light and flexible but strong sheet of material having a fibre center and one or more lining sheets attached thereto in such a manner as to hold the heterogeneously formed mass firmly in place in the structure. The improvements are also directed toward providing a composite felted bat or center in which a cheap, weak and poorly felted material may be used in combination with a means for strengthening it and binding the contact and adhesion between the center and facing or liners that are applied to the opposite faces thereof.

To these and other ends the invention resides in certain improvements and combinations of parts, all as will be hereinafter more fully described, the novel features being pointed out in the claims at the end of the specification.

In the drawings:

Figure 1 is a perspective view of a fragment of insulating material constructed in accordance with and illustrating one embodiment of my invention, portions of the liner sheets being cut away to reveal interior elements;

Figure 2 is a longitudinal section therethrough, and

Figure 3 is a transverse section on the line 3-3 of Figure 2.

Similar reference numerals throughout the several views indicate the same parts.

This invention is an improvement upon that disclosed in the prior application, Serial No. 256,249, filed February 23, 1928, in which is described the general structure of the preferred form of my insulating bat. Referring briefly to this general structure, the central body of felted fibrous material is indicated generally at 1, and the larger proportion thereof may consist of a flocculent mass constituted as hereinafter described and 50 felting down to a soft spongy condition that

is porous and resilient. There is applied to one or both surfaces thereof a plurality of narrow thin flexible strips 2 and 3 that are laid in parallelism longitudinally of the bat strip, and spaced laterally from each other as shown in Fig. 1. Ordinarily we use paper for this purpose, and where the strips are applied to both sides of the bat the units on one side are respectively placed opposite corresponding units on the other side. We then sew the bat and strips together with longitudinal rows of stitching 4. In some cases we use double rows of stitching on some of the interior strips as shown. Finally there is applied to one or both sides of the resulting structure a flexible liner sheet 5 of paper or other material, previously coating the under side of the liner with an adhesive body 6, such as a solution of silicate of soda, asphaltum, glue or other appropriate substances known in the paper making art. This adhesive may be applied to the entire face of the liner, so that it adheres directly to the bat 1, or it may be applied along lines corresponding to the strips 2 and 3, or it may be applied to the strips instead of to the liner. In any event, its function is to firmly attach the liner to the sewn strips, as shown in section in Figs. 1 and 2, and not only this but to cement and lock the exposed ends of the stitches 4 in place, they being imbedded in the adhesive body, so that they do not give and enlarge the holes in the strips through which they pass.

Asphaltum is preferably used as the adhesive element where waterproofing of the outer paper liners is desired, or other adhesives of a waterproofing character can be used or waterproofing may be effected by a treatment additional to the application of the adhesive.

In the practice of my present invention, in the composition of the central body 1, we find it both convenient and economical to use a low grade of cotton, such as damaged or waste cotton, as the principal constituent. The fibres thereof being short and weak they felt poorly, and as most of them are not long enough to reach from one adhesive liner 5 to the other there is nothing to prevent the bat from

splitting and tearing under severe treatment. We therefore intersperse this material with a quantity of longer and stronger fibres of another material which, associated therewith in a heterogeneous mass holds the weaker material together and in place and at the same time runs back and forth in contact with the adhesive walls of the liner at innumerable points binding them together. The material we prefer to use for this purpose is jute, the fibres of which are indicated at 7 in the drawings. The proportion thereof is preferably from ten to thirty per cent according to its own quality and the quality of the cotton or weak material.

15 It is to be understood that we do not limit ourselves to the combination of materials specifically referred to, as the principal idea is to use a weak material that is cheap and incapable of binding in combination with an interspersed stronger and longer material which has this capability.

We claim as our invention:

1. As an article of manufacture, a composite insulating material embodying in combination a felted bat of loosely associated heterogeneous fibres of one nature and material, the same being interspersed with stronger and longer fibres of a different nature and material, stitching distributed therethrough and adapted to extend from one side of the material to the other and thin liners secured to opposite sides of the bat, by means of adhesive material, said liners adapted to support the stitching in sustained reenforcing position.

2. As an article of manufacture, a composite insulating material embodying in combination a felted bat of loosely associated heterogeneous fibres of one nature and material, the same being interspersed with stronger fibres of a different nature and material, strips disposed on either side of the bat, stitching supported over said strips and extending through the bat for the purpose of reenforcing the same, liners secured to opposite sides of the bat by means of adhesive material and adapted to secure the stitching in position.

50 CHARLES A. UPSON.
HUGH M. SPENCER.
